UNITED STATES PATENT OFFICE.

HAROLD E. ZIEGLER, OF DUNCAN, OKLAHOMA.

DRAW WORKS.

Application filed August 8, 1925. Serial No. 49,046.

The object of this invention is the provision of a speed control for working lines or cables in deep well drilling apparatus of the rotary type.

5 A further object is the provision, in that part of a deep well drilling apparatus known as the draw works with twin line or cable drums and means for driving the drums either separately or jointly at varying desired speeds in accordance with the speed and power required in the drilling operation, the said driving means being under the instant control of the operator so that less delay will be occasioned in the drilling than 10 is common with ordinary devices for a similar purpose.

A further object is the provision of a draw works with twin drums having the ends of the pull line attached thereto and means for 20 locking either of the drums on a common shaft whereby the line on the locked drum is employed as a pull or working line and that on the other drum as a dead line, means being provided for holding the last mentioned drum from turning, means being further provided for locking both of the drums on the shaft, whereby both ends of the line may be used as a pull or fast line, while 25 means, under the immediate control of the operator, is provided for imparting varying desired speeds to the drum carrying shaft.

A further object is the provision of a draw works having twin drums thereon and on which the respective ends of the lines or 35 cables are secured, and in which said drums are susceptible to a power range of a great number of speeds at the will of the operator without delay in the operation; wherein the drill line may be easily fed off of one 40 onto the other drum so that well spooled lines are at all times insured and thereby prolonging the life of the line, and further wherein both ends of the line may be pulled onto one drum, baring the other for the 45 sand line and using an idle pulley in the traveling block for the crown pulley.

A still further object is the provision of an apparatus for this purpose in which friction between cooperating parts is reduced to 50 insure the longer life thereof and as a consequence enabling the operator to use a lighter and less expensive traveling block with equal efficiency, and further wherein the rig, while of a comparatively simple construction, is properly balanced without in-

creasing the size or adding to the weight of the parts thereof.

To the attainment of the foregoing, and many other objects which will present themselves as the nature of the invention is better understood, reference is to be had to the drawings, in which there is illustrated a satisfactory embodiment of my improvement as it now appears to me, it being understood that the said drawings are merely 60 illustrative and that I may resort to such changes therefrom as fall within the scope of what I claim.

In the drawings:

Figure 1 is a side elevation of a draw 70 works in accordance with this invention.

Figure 2 is a sectional view on the line 2-2 of Figure 1.

Figure 3 is a sectional view on the line 3-3 of Figure 2.

Figure 4 is a sectional view on the line 4-4 of Figure 1.

Figure 5 is a sectional view on the line 5-5 of Figure 2.

Figure 6 is a detail sectional view through 20 a portion of the brake band operating mechanism.

Figure 7 is a sectional view on the line 7-7 of Figure 5.

Figure 8 is a detail perspective view looking 85 toward one end of the body member of one of the drums.

The inside head board of the frame of my improved draw works is indicated in the drawings by the numeral 1. The end jack posts are indicated by the numerals 2, and the central jack post by the numeral 3. Journalized in suitable bearings in the jack posts there is the line shaft 4. The line shaft has on its ends the usual cat heads 5.

95 Fixed on the line shaft 4, inward of the jack posts 2, there are sprocket wheels 6 and 7, respectively. The sprocket wheel 6 is larger than the sprocket wheel 7, the said wheel 6 carrying 13 teeth, while the sprocket 100 wheel 7 carries 11 teeth.

105 Loosely arranged on the line shaft there is another sprocket wheel 8. This wheel 8 is held from longitudinal movement on the shaft in one direction by the contacting engagement thereof with a sleeve 9 that is fixed on the same line shaft. The sprocket wheel 8 has trained therearound an endless chain that drives the rotary machine, of the ordinary construction, (not shown).

In addition to the sprocket wheels above described, there is freely mounted on the shaft between the left hand jack post 2 and the central post 3 of the frame, two other sprocket wheels, indicated by the numerals 10 and 11, respectively. The sprocket wheel 10 is of a materially greater diameter than the sprocket wheel 11, and both of these wheels have trained therearound chains that are connected to the engine, (not shown). The sprocket wheels 8, 10 and 11, have outwardly extending hubs 12, 13 and 14, respectively. The hubs have their outer faces notched for engagement with lugs 15, respectively formed on the faces of slideable clutch members 16, 17 and 18, respectively. The slideable clutch members are mounted in splines on the line shaft, and are cylindrical in cross section, with peripheral grooves in which are seated ring members 19 that are straddled by the forked ends of levers 20, 21 and 22, respectively. Each of the rings 19 is provided with oppositely disposed outwardly directed studs that pass through elongated slots in the forked arms of the levers. The lever 20 is pivotally supported on a bracket 23 secured on the inner face of the right hand jack post 2, while the levers 21 and 22 are pivotally suspended from the head board 1. The levers 21 and 22 are pivotally connected to a rod 24, the outer end of the rod, in turn, being pivoted to an operating lever 25 which depends from and is pivotally secured to the head board 1. The swinging of the operating lever 25, in one direction will cause the lug 15 on the clutch 18 to be received in the notched hub 14 of the sprocket wheel 11, this swinging of the lever swinging the clutch member 17 farther away from the hub 13 of the sprocket wheel 10. A reverse swinging of the lever 25 will bring the clutch member 17 into clutching engagement with the hub 13 of the sprocket wheel 10 and move the clutch member 18 not only out of but a distance away from the notch in the hub 14 of the sprocket wheel 11. In this manner it will be noted that a confusion in clutching the sprocket wheels to the line shaft will be obviated. The lever 20 is centrally pivoted to the bracket 23 and has loosely connected to its upper and outer end a rod 26. The rod 26 has its outer end provided with spaced openings through any one of which there is passed a pivot that also passes through the end of an operating lever 27. The lever is pivoted to the head board 1 but has its handle disposed adjacent to that of the operating lever 25. The swinging of the lever 27 in one direction will move the clutch block 16 to lock the sprocket wheel 18 on the line shaft and the swinging of the lever in an opposite direction releases the clutch 16 and frees the sprocket wheel.

65 Journaled in suitable bearings below the

line or drive shaft 4, on the opposite sides of the posts on which the bearings for the said line shafts are secured there is a driven or drum shaft 28. Loosely mounted on the shaft 28, directly inward of the end jack posts 2, there are sprocket wheels 29 and 30, disposed in alignment with the respective sprocket wheels 6 and 7 on the shaft 4. The sprocket wheel 30 is materially larger than wheel 29, and has 36 teeth thereon while the sprocket wheel 29 is provided with 27 teeth. Trained around the sprocket wheels 6 and 29, there is an endless chain 31, and likewise trained around the sprocket wheels 7 and 30, there is a similar chain 32. Suitable means are provided for holding the sprocket wheels 29 and 30 from longitudinal movement on the shaft 28.

The sprocket wheels 29 and 30 have their inner or confronting ends provided with hubs having clutch surfaces 33 and 34, respectively. These clutch surfaces are designed for engagement with clutch surfaces on slideable blocks 35 and 36, respectively, and the said blocks are mounted in spline-ways on the shaft 28. The clutch blocks or members 35 and 36 are round in cross section, and are provided with peripheral grooves in which there are seated ring members 37 and 38, respectively. These rings are straddled by the forked ends of levers 40 and 41, respectively. The rings are provided with oppositely disposed outstanding lugs that are received through slots in the arms at the forked ends of the said levers 40 and 41.

On the base 42 that supports the posts 2 and 3 there are secured upstanding brackets 43 and 44, respectively. Each bracket has a widened laterally extending head 45, and to the laterally extending portion on one end of each of the heads there are pivoted levers 40 and 41. The lever 40 has an angle end to which is pivoted a link 45'. This link 45' in turn is pivotally secured to a foot pedal 46 which has one end pivotally supported on the base 42. To the lower end of the lever 41 there is pivotally secured a rod 47 directed toward the left hand side of the frame, and this rod is pivoted to the offset end of a crank shaft 48 which is journaled in a suitable bearing 49 and has one of its ends extended angularly to provide a foot pedal 50.

Pressure on the foot pedals 46 and 50 will actuate the levers 40 and 41 to throw the clutch blocks 35 or 36 into clutching engagement with the clutch surfaces on the sprocket wheels 29 or 30, and thereby lock either one of the said sprocket wheels on the shaft 28.

Arranged for longitudinal movement on the shaft 28, and disposed opposite the clutch blocks 35 and 36, there are other and similar clutch blocks 51 and 52, respectively.

These clutch blocks have their clutch surfaces directed toward each other, being disposed opposite to the clutch surfaces on the blocks 35 and 36. The clutch blocks 51 and 52 are provided with peripheral grooves in which are seated rings 53 and 54 respectively. These rings are straddled by the bifurcated ends of levers 55 and 56, respectively. The rings are provided with oppositely directed studs received through slots in the arms at the bifurcated ends of the said levers 55 and 56 which are pivotally secured to the inner lateral extensions of the heads 45 of the brackets 43 and 44, the lever 56 having pivoted to its lower end a rod directed toward the left hand jack post 2, the said rod having its free end pivotally secured to an offset or crank shaft, similar to the shaft 48. This crank shaft is also 20 journaled in suitable bearings on the base 42 and has an outer angle arm terminating in a foot pedal 57. By depressing the foot pedal the clutch block 52 will be moved inwardly on the shaft 48. The lever 55 has 25 pivotally secured to its lower end a link 55' that is likewise connected to a lever 58 that is journaled in a suitable bearing in the base 42. The lever 58 has an offset end that terminates in a foot pedal 59. A pressure on 30 this foot pedal will swing the lever 55 to move the clutch block 51 toward the center of the shaft 28.

The rings 37 and 53, as well as the rings 38 and 54, are provided with aligning openings, and through these openings there are passed bolts 60. On the ends of the bolts there are screwed nuts 61 which contact with helical springs 62 on the outer portions of the said bolts. The springs 62 also contact 40 with the rings 53 and 37, thereby forcing the oppositely disposed pairs of clutch blocks toward each other and moving the said clutch blocks to unclutching positions.

On the shaft 28 there are freely journaled 45 twin drums, each being broadly indicated by the numerals 63 and 64, respectively. As both of the drums are of a similar construction, a detailed description of one may be taken as equally applicable to the other. Each drum has its body portion in the nature of a tube 65 and each body 65 is centrally cored out to provide an oil reservoir 66. The body is provided with a suitable oil inlet, and the oil is delivered onto roller bearings 67 that are seated in annular grooves provided adjacent to the ends in the bore of the tube. The outer and reduced ends of the tubes 65 have their sides flattened for reception in similar openings in the heads 68 and 69 for the said drum. The heads 68, which are arranged at the confronting ends of the said drums 63 and 64, are in the nature of discs, and each of these discs is provided with an annular series of equidistantly spaced openings 70, the purpose of which

will be presently apparent. The outer heads 69 are also in the nature of discs, but are provided with peripheral flanges 71. The discs providing the heads 69 proper have secured on their inner faces castings whose body portions are in the nature of discs 72. Each of the body portions is formed with an outstanding hub 73 provided with an inwardly directed flange 74 that confronts with the outer end of the tubes 65 of the said drum. The bore of the hub coincides with the shape of the ends of the tubes 65 received therein. The hub 73 is provided with oppositely arranged notches 75, the outer walls of which are inclined. These notches are designed to receive therein the lugs or projections 75' on the respective slideable clutch blocks 51 and 52, when either of the drums 63 or 64 is to be locked on the shaft.

The flanges 71 of each of the drums 63 and 64 have arranged therearound brake bands 76 and 77, respectively. One end of each of the brake bands is anchored to a rod 78 whose ends are supported in standards 79 secured to and arising from the base. The second end of each of the brake bands is looped and through this loop there is received the cranked portions 80 or 81, formed on shafts 82 and 83, respectively. By reference to Figure 6 of the drawings it will be noted that the shaft 82 has its straight portions hollow so that the shaft 83 passes therethrough and finds a bearing therein. The bearings for the shaft 82 are indicated by the numerals 84, and these bearings may also support the uprights 79. Fixedly secured to the ends of the shafts 82 and 83, at points adjacent to the left hand jack posts 2, there are upwardly directed levers 85 and 86, respectively. Thus by operating either of the levers the brake bands of either of the drums may be tightened to regulate the speed of the said drums when the same have been clutched to the shaft 28.

The heads 70 of the respective drums 63 and 64 are arranged at the opposite sides of the central post 3 of the frame, and fixed on this post, directly above the bearing thereon for the shaft 28 there is a housing 87. The bore of this housing is rounded, and in the said bore there is freely arranged a cross sectionally rounded bolt 88 having beveled ends and which is provided with a stem 89 terminating in a head 90. The stem 89 is normally received in the lower portion 91 of a substantially V-shape notched slot 92 in the outer face of the housing 87. The stem 89 passes through an opening in a bar 93 which has an upper slotted portion 94 through which there is passed a headed pin 95 that anchors it to the post 3. The upper end of the bar 93 is pivoted, as at 96, to a lever 97. The lever has an elongated slot 98 therethrough and through this slot there is

passed a headed pintle 99 secured in the bracket 100 on one face of the central post 3. By swinging the lever 97 downwardly the stem 89 of the bolt 88 will be brought out of the notch 91 and arranged in the slot 92. By exerting a push or a pull on the lever 97 the bolt 88 may be moved into one of the openings 70, on either of the heads 68 of the drums 63 or 64, thus locking one of the drums from turning. The reverse movement of the lever 97 will cause the stem 89 to travel in the slot 92 and to be again received in the notch 91, thus unlocking the drum.

The engine driven sprockets 10 and 11 on the line shaft 4 are butted back to back and held in place by the splines for the clutch blocks 13 and 14. The sprocket 10 is larger than the sprocket 11 as shown in Figure 1.

The clutch blocks 13 and 14 are alike and interchangeable, and as above stated, it is impossible to engage one clutch assembly without first disengaging the other. The clutch blocks on the drum shaft 28 are likewise alike and interchangeable and being arranged in pairs which are back to back they must ride in the proper direction either to clutch or unclutching positions. The drums, as previously stated, are also alike and are interchangeable. The inside drum heads are preferably formed of semi-steel. The U or crank shafts associated with the brake bands effect a positive gripping of the said bands with the drum heads. The bands have asbestos linings to insure the positive gripping engagement thereof with the brake heads, and the levers for the brake shafts or rods are screwed into heads which are arranged around the said rods, (see Figure 6).

The operating engine for the device has not been illustrated, but in Figure 1 of the drawings the numeral 101 designates a wheel for operating the engine throttle and the numeral 102 indicates a rod, which when actuated, will reverse the turning of the engine.

We will suppose, for example, that the operator has 8 lines strung up and is drilling 8000 feet, (a depth as yet unreach). The bit is dull and must be pulled out. The operator pulls the rod 102 and reverses his engine. He then pushes clutch lever 27 to bring the clutch block 16 out of clutching engagement with the sprocket wheel 8 connected with the rotary machine. He next pulls on lever 25 to cause the clutch block 15 to engage with the clutch surface 13 of the engine sprocket wheel 10 and steps on the pedals 46 or 50 depending upon which drum 63 or 64 he wishes to first use. At the same time he pulls the lever for operating either the clutch block 51 or 52, locking one of drums to the shaft and likewise locking the other drum that is to be held stationary, by actuating the lever 97. By bringing the clutch 36 into engagement with the

clutch surface on the sprocket wheel 30 he obtains a slow speed. With full steam ahead he is pulling with eight lines in low gear. After pulling 1000 feet on the pipe the operator may disengage the drive sprocket 10 and by operating the lever 25 moves the clutch 18 into clutching engagement with the sprocket wheel 11, thereby gaining speed of operation. After lifting another 1000 feet he may reverse this procedure, again by declutching the sprocket wheel 11 and clutching the sprocket wheel 10 on the shaft. The drum is then driven by the sprocket chain 31. At another 1000 feet the drum is caused to revolve at a faster speed by declutching the sprocket wheel 10 and clutching the sprocket wheel 11 on the shaft 4, the drum shaft being still driven by the sprocket chain 31. The pipe is now half out of the hole.

At this point the operator is safe to use the two drums, which have the respective ends of the lines or cables secured thereto. When using both drums the speed will be doubled, and by operating the clutches 16 and 17, in a manner as above described, four separate and distinct speeds may be imparted to the two drums.

In the first mentioned operation, that is when only one drum is driven, four different and distinct speeds are imparted to the drum, and at the second operation, that is when the drums are locked together on the drum shaft four separate and distinct speeds are imparted to the locked drums. Thus a great number of separate and distinct speeds of the drums are provided for.

The advantages of my improvement over a similar construction will, it is believed be perfectly apparent to those skilled in the art to which this invention relates, and while I have illustrated a satisfactory embodiment of my improved device my features of invention are capable of extended application and I do not wish to be limited to the structure herein shown and described. It is to be understood that the clutch blocks 16, 17 and 18 on the line shaft are alike and interchangeable and the ends of the locking pins 88, (Figure 4) should be beveled to automatically unlock as the drum moves forward, upon engagement of the drum clutch. The drum braking surface 71, (Figure 5) is concaved so that the asbestos brake lining is convex in order to conform thereto. The brakes are for the purpose of controlling the speed of rotation of the drums when the said drums are unclutched from the shaft 28. The splines under the clutch blocks 52, 36, 51 and 35 offset each other so that when the clutch blocks are disengaged they will butt back to back against themselves and against the spline ends. The brake band crank shafts 82 and 83, should rig up 9 inches back of standards 79 (Figure 1), while the top ends of the brake levers 85 and 86 come to-

gether as disclosed by the drawings so that the operator may actuate them simultaneously with one hand as will be apparent.

Having described the invention, I claim:—

- 5 1. In a draw works, the combination of a frame, a shaft, two drums freely journaled on the shaft, said drums having their confronting heads provided each with an annular series of apertures, a bolt member mounted in the frame and movable into one of the apertures of either head for locking the drum thereof against movement, said bolt being normally in inactive position, clutching means on the shaft, operating means for 15 said clutching means to cause the same to engage with either of the drums to lock one or both of the drums to the shaft, and means for revolving the shaft at varying predetermined speeds to impart like speeds to the 20 drum or drums clutched to the shaft.
2. In a draw works, the combination of two drums, freely journaled on a shaft, and a cable having its ends secured on each of said drums, said drums having their confronting heads provided with spaced circumferential apertures, a housing having a notch between said heads, a bolt member in the housing having a stem projecting through the notch, a lever operated means 25 associated with the stem, for causing the latter to ride on either end angle walls of the notch to bring the bolt into one of the openings on either head to lock the drum thereon against movement on the shaft, clutch means on the shaft engaging the outer faces 35 of the drums, pedal operated means for actuating said clutch means for locking one or both of the drums on the shaft, and means for revolving the shaft at varying predetermined speeds for imparting like motion 40 to the drum or drums clutched thereto.
3. In a draw works, a frame, a drum shaft journaled on the frame, twin drums on the drum shaft, means between the confronting heads of the drums engageable with said 45 heads for locking either of the drums to the frame, said means being normally inactive, clutch surfaces on the outer heads of the drums, clutch blocks splined on the drum shaft movable to engage said clutch surfaces, spring means holding the clutch blocks out of clutching engagement, pedal operating means for moving the clutch blocks and the clutching engagement, brake bands for the outer ends of the drums, a 50 crank shaft secured to the free ends of the brake bands and the lever actuating means for operating the crank shaft.

In testimony whereof I affix my signature.

HAROLD B. ZIEGLER.
